LEONARD KEBLER, OF BRONXVILLE, NEW YORK, ASSIGNOR TO WARD LEONARD
ELECTRIC COMPANY, A CORPORATION OF NEW YORK

RESISTANCE UNIT

Application filed July 19, 1930. Serial No. 469,043.

This invention relates to resistance units, and particularly to that form in which the resistive conductor is wound upon an insulating tubular support and provided with terminal connections. The invention particularly relates to the provision of auxiliary terminal conductors which are connected to the resistive conductor and supplementary clamping means for holding the terminal conductors in place upon the insulating support. The invention is an improvement upon that disclosed in the pending application of Frederic H. Bullinger, Serial Number 467,674, filed July 14, 1930, the particular object of the present invention with relation thereto being the provision of terminal connections and supporting means by which the unit may be supported, or for uses where it is desired to provide terminal connections other than flexible lead wires.

Resistance units of this type are usually covered with an adhesive insulating coating such as vitreous enamel, cement and the like; and one object of the present invention is to provide terminal connections of the above character and supporting means, therefor, such that there will be no objectionable bump or projection on the tube which cannot readily be covered by the insulating coating. Another object is to overcome the objection in previous units having terminal connections of the above character where sheet metal bands of copper have been used, which objection arises from the fact that the coefficient of expansion of copper is so much more than that of the insulating support. During the firing operation for maturing the insulating coating, the prior copper bands sometimes shift on the insulating support and cause loosening or shifting of the resistive conductor, with the possible occurrence of short-circuits therein; also, the undue expansion of the sheet metal copper terminals makes it difficult to insure the proper covering of the copper bands with the insulating coating. By means of the present invention, the use of sheet metal copper bands is avoided and replaced by encircling and clamping elements of sheet iron or steel, or similar metal, which not only has higher

tensile strength than that of copper, permitting the encircling element to be smaller and more easily covered by the insulating coating, but also, by reason of its coefficient of expansion being lower than that of copper, avoiding the objectionable effects above referred to when sheet copper encircling clamping elements are used.

However, I still retain the advantage of permitting the use of copper terminals and so relate them to the resistive conductor and clamping element as to provide for connection to the external circuit through direct contact with the low resistance terminal, such as copper. Another object of this invention is to replace the prior sheet metal encircling and clamping element of copper by metal of lower cost, such as strips of sheet iron or steel, making the unit less expensive in cost of material.

Another object is to provide a construction which will be rigid where it leaves the insulating coating and strongly support the sheet metal terminal in that region, so that when the unit is handled and external connections made thereto, it will not bend where it leaves the insulating coating. I thereby avoid cracking or breaking away of the insulating coating at that region. This applies particularly to units where the projecting portions of the copper terminals are made flexible for convenience of making connections and of cleaning the contacting surfaces.

Another object is to provide means, in cases where desired, for giving the entire terminal strength and stiffness and yet secure direct contact connection with the terminal strip, such as of copper. Another object is to secure ease in assembly of the parts and also insure strength of the assembly, by uniting the conducting terminal with the clamping element before mounting the parts upon the insulating support. Other objects and advantages of this invention will be understood from the following description and accompanying drawing.

Fig. 1 is a longitudinal section of one form of resistance unit embodying my invention; Fig. 2 is a side elevation of the

same, showing the parts before the application of the insulating coating; Fig. 3 is a similar elevation of the opposite side from that shown in Fig. 2; Fig. 4 is a development of the conducting terminal; Fig. 5 is a development of the clamping and supporting element; Fig. 6 is a longitudinal section of another embodiment of the invention; Fig. 7 is a side elevation before the application of the insulating coating; Fig. 8 is a similar view showing the opposite side from that shown in Fig. 7; Fig. 9 is an end view of the parts before the application of the insulating coating; Fig. 10 is a development of the conducting terminal; and Fig. 11 is a development of the clamping and supporting element.

Referring to Figs. 1 to 5, the insulating tubular element 1, usually of porcelain, is shown having the resistive conductor 2 wound thereon. The conductor 2 is electrically connected at the ends, or at any intermediate point desired, to the conducting terminal 3. This is stamped out from sheet metal, preferably of copper, in the form shown in Fig. 4. It has a portion 3a extending outwardly from the tube, and an inner portion 3b which lies directly on the surface of the tube and extends in a circumferential direction thereon. This element, in the form shown, is provided with a pair of oppositely located ears 3c, the sides of which are cut inwardly in the body of the conducting strip, as indicated in Fig. 4. One side of the strip is provided with a tongue 3d to which the resistive conductor is connected.

The iron or steel clamping and supporting element for the terminal, shown in Fig. 5, has a long narrow portion 4 which encircles the main portion of the tube; and at one end is provided with an enlarged portion 4a. The opposite end is provided with an enlarged portion 4b, and oppositely located outwardly extending ears 4c. At opposite locations, portions are cut away to form indentations 4d.

In assembly, the conducting terminal is first secured to the inside of the clamping element by bending the ears 3c of the terminal outwardly and inwardly so as to embrace the neck portion 4e of the clamping element, as shown in Fig. 2. The parts are then bent substantially at right-angles along ing center lines indicated in Figs. 4 and 5. Then the parts are mounted upon the insulating support, the narrow portion 4 of the clamping element encircling the support and bringing the part 4a thereof towards the part 4b with the conducting element extending outwardly between and beyond the end portions of the clamping element. The ears 4c are then bent around the parts and inwardly, so as to firmly bind the end portions of the clamping element against each

other with the conducting element between them, as shown in Fig. 3. One end of the resistive conductor is then wound with a few turns around the tongue 3d of the conducting terminal at the left, or otherwise secured thereto, and then passed over the narrow portion 4 of the clamping element and under a slightly upturned corner of the terminal conductor, as indicated at the left in Fig. 2, and is then wound around the supporting element and wound with a few turns around the tongue 3d of the right-hand terminal. The insulating material for forming the coating is then applied over the resistive conductor and over the parts of the conducting and clamping elements which embrace the tube, after which the unit is fired or otherwise treated to mature and form the permanent insulating coating 5, preferably vitreous enamel. In this form of my invention, the outwardly extending portions 3a of the conducting terminals are flexible for convenience of making connections and cleaning the surfaces, but it is evident that the portion of the conducting terminal near the tubular support and in the region of the insulating coating is prevented from having any flexibility by the enlarged end portions of the clamping element firmly binding and supporting the portion of the conducting terminal where it extends outwardly. This avoids any danger of cracking or breaking away of the enamel, during handling or use, at the terminals. It is also apparent that the parts surrounding the tubular support have no objectionable protuberances, and also are of comparatively small size and capable of being conveniently and well covered and protected by the insulating coating.

In the form shown in Figs. 6 to 11, the conducting terminal 6 is shown in development in Fig. 10 as of general rectangular form having perforations 6a, 6b, 6c and 6d. It is also provided with a tongue 6e to which the resistive conductor is secured. The center lines in Fig. 10 indicate the lines along which the terminal is bent after being assembled. The conducting element is preferably made of copper, or similar material.

The clamping element is shown in development in Fig. 11 as having a narrow portion 7 which extends around the main portion of the insulating tube. It has enlarged portions 7a and 7b at its ends with opposite outwardly extending ears 7c on the end portion 7a. It also has perforations 7d to 7e. The center lines in Fig. 11 indicate lines along which the clamping element is bent when assembled. The clamping element is preferably made of iron or steel, or of metal having similar characteristics.

Before mounting the parts upon the insulating support, the conducting terminal is secured to the clamping element, such as by punching one of the holes 6c or 6d into one

of the holes 7e or 7f of the clamping element and forcing part of the copper metal slightly over the edge of one of the holes 7e or 7f, or they may be riveted or spot-welded, or secured together by ears of one part enveloping the other, as described with reference to Figs. 1 to 5, or otherwise. The parts are then bent substantially at right-angles along the center lines above referred to, except that the conducting terminal is not bent along the upper center line of Fig. 10. The parts are then mounted on the tubular support, the narrow portion 7 of the clamping element encircling the tube and the outer parts of the clamping element are brought together with the outwardly extending portion of the conducting terminal between them. The ears 7c are then bent around the parts so as to firmly clamp the outwardly extending portions together. The outer portion of the terminal is then bent on itself so as to extend inwardly towards the tube, as shown in Fig. 9, so as to form an exposed copper surface for connection in circuit as may be desired. A screw 8 is then passed through the holes 6a, 6b, 7d and 7i of the terminal structure and provided with the usual nuts for clamping the parts together and for securing the external leads thereto. The resistive conductor is then connected to the conducting terminals and wound upon the insulating support, as described with reference to Figs. 1 to 5, after which the insulating coating is applied as already described. The holes 6c and 6d of the terminal coincide with the holes 7e and 7f of the clamping element permitting the enamel, or other insulating coating to pass through them and engage the tubular support, as likewise through the hole 7g and 7h of the clamping element, so that the insulating coating will serve to hold the clamping element in more intimate engagement with the support and be more firmly united therewith.

It is apparent that the structure of Figs. 6 to 11 has the advantages already generally referred to and that instead of having flexible terminals as in Figs. 1 to 5, the whole external portions of the terminals are rigid and strongly supported.

Although I have described preferred embodiments of this invention, it is susceptible of various modifications without departing from the scope thereof.

I claim:

1. A resistance device comprising a support, a resistive conductor thereon, a sheet metal element embracing said support by one face thereof, a sheet metal conductive terminal held in position on said support by said sheet metal element, one face of said conductive terminal being against said support and the other face against said sheet metal element, said resistive conductor be-

ing directly mechanically and electrically connected to said sheet metal conductive terminal, said sheet metal element having greater tensile strength than the metal of the conductive terminal, and an insulating coating covering said resistive conductor and at least a part of said sheet metal element. 70

2. A resistance device comprising a support, a resistive conductor thereon, a sheet metal element embracing said support by one face thereof, a sheet metal conductive terminal held in position on said support by said sheet metal element, one face of said conductive terminal being against said support and the other face against said sheet metal element, said resistive conductor being directly mechanically and electrically connected to said sheet metal conductive terminal, said sheet metal element having a lower coefficient of expansion than that of the metal of said conductive terminal, and an insulating coating covering said resistive conductor and at least a part of said sheet metal element. 75 80 85 90

3. A resistance device comprising a support, a resistive conductor thereon, a sheet metal element clamping said support and having outwardly extending end portions, a sheet metal conductive terminal held in position on said support by said element, and having an outwardly extending portion between the said outwardly extending portions of said sheet metal element, said sheet metal element having higher tensile strength and a lower coefficient of expansion than the metal of said conductive terminal, and an insulating coating covering said resistive conductor and at least a part of said sheet metal element. 95 100 105

4. A resistance device comprising a tubular support, a resistive conductor wound thereon, a sheet metal element embracing said support and having enlarged end portions, one of said end portions having projections bent around the other of said end portions for clamping the element in position, a conductive terminal clamped between said element and said support and having an outwardly extending portion located between said end portions of said sheet metal element, and an insulating coating covering said resistive conductor and at least a part of said sheet metal element. 110 115

5. A resistance device comprising a tubular support, a resistive conductor wound thereon, a sheet metal element embracing said support and having its ends connected together, a sheet metal conductive terminal clamped between said support and said element, said resistive conductor being directly mechanically and electrically connected to said sheet metal conductive terminal, means for securing said element and terminal together, said terminal having a portion ex- 120 125 130

tending between and outwardly beyond the ends of said element and supported thereby, and an insulating coating covering said resistive conductor and at least a part of said 5 element.

6. A resistance device comprising a tubular support, a resistive conductor wound thereon, a sheet metal element embracing said support and having its ends connected 10 together, a sheet metal conductive terminal clamped between said support and said element, said resistive conductor being directly mechanically and electrically connected to said sheet metal conductive terminal, said 15 terminal having a portion thereof embracing said element for securing them together, said terminal having a portion extending between and outwardly beyond the ends of said element and supported thereby, and an 20 insulating coating covering said resistive conductor and at least a part of said element.

7. A resistance device comprising a tubular support, a resistive conductor wound 25 thereon, a sheet metal element embracing said support and having enlarged outwardly extending portions, a conductive sheet metal terminal between said outwardly extending portions and extending beyond the same, 30 said sheet metal element having higher tensile strength and a lower coefficient of expansion than the metal of said conductive sheet metal terminal, said resistive conductor being directly mechanically and electrically 35 connected to said conductive sheet metal terminal, and an insulating coating covering said resistive conductor and at least a part of said element.

8. A resistance device comprising a tubular support, a resistive conductor wound thereon, a sheet metal element embracing said support and having enlarged outwardly extending portions, a conductive sheet metal terminal between said outwardly extending 45 portions and extending beyond the same and also bent inwardly over the end of one of said end portions, said sheet metal element having higher tensile strength and a lower coefficient of expansion than the metal of 50 said conductive sheet metal terminal, said resistive conductor being directly mechanically and electrically connected to said conductive sheet metal terminal, and an insulating coating covering said resistive conductor 55 and at least a part of said element.

LEONARD KEBLER.
